HOIST BRAKE AND CONTROL SYSTEM

Harry F. Vickers, Detroit, Mich., assignor to
Vickers, Incorporated, Detroit, Mich., a corpora-
tion of Michigan

Application December 15, 1939, Serial No. 309,459

5 Claims. (CL 192—144)

This invention relates to a hoisting control system.

In hoisting systems in which the motive power is liquid under pressure, two problems arise. One is to keep the pressure lines between the source and motor filled with liquid; another is to provide an effective means for releasing the brake on the hoist.

An object of the present invention is to provide brake release means which requires a relatively small source of auxiliary pressure for operation.

A further object is to provide a means associated with the auxiliary pressure system for maintaining the proper volume of power liquid functioning between the source and the hoisting motor. Another object of the invention has to do with the provision of a novel control means whereby the travel of the hoist can be accurately controlled.

Other objects and features of the invention, having to do with details of construction and operation, will be brought out in the following description and claims.

In the drawing:

Fig. 1 is a circuit diagram showing the essential elements of the invention.

Fig. 2 is a detailed view of the brake mechanism used for the hoist.

Referring to the drawing, a hoist drive wheel is shown at 10 arranged to be driven through gears 11 and 12 rotated by a reversible hydraulic motor 13. A reversible variable delivery pump 14 supplies fluid under pressure to the motor 13 through lines 15 and 16 used alternately as pressure or exhaust lines. An electric motor 17 or other source of power drives the pump 14 and also a pilot pump 18.

The reversible pump 14 has a movable member 20 which may be shifted in one direction or another to determine the direction of flow through the pump 14 and the direction of the motor 13. A hand lever 21 is connected to the member 20 through linkage 22, 23, which is connected by a spring 24. Movement of the hand lever 21 to the hoist position indicated, will shift pump 14 off-center upwardly to cause flow of liquid under pressure to line 15. Ignoring for the moment the braking mechanism, it will be seen that a threaded shaft 25 is connected at one end to a bracket 26. A gear nut 27 runs off from the gear 11 and, consequently, shifting of the hoist wheel 10 will cause a shifting of the shaft 25. The bracket 26 is directed to a cam table 28 on which is a hoist cam 29 and a lowering cam 30. A lever 31 is pivoted at 32 on a stationary upright 33. 55

Each end of the lever 31 is provided with a downward projection which is adapted to cooperate alternately with the two cams 29 and 30. The right end of lever 31 is pivoted at 34 to link 23 so that the movement of the cams may control the movement of the member 20 on the pump. Consequently, at the end of each movement of the hoist, there will be a proper deceleration and stopping.

10 An output pipe 40 from pump 18 leads to a cylinder 41 and also to a valve block 42 through branches 43 and 44, respectively. Cylinder 41 has a free piston 45 located therein backed by a spring 46. Spaced from the inlet end of the cylinder 41 is an outlet pipe 47. This cylinder will serve as a reservoir for the output of the pump and also as a bypass outlet when the liquid stored in the cylinder 41 is subjected to such a pressure that the free piston 45 will be moved down against spring 46 to allow bypassing through pipe 47. Branch 44 leads directly through the housing 42 to a directional valve 48. This valve consists of a shaft which has spaced spools 49, 50, 51, 52 and 53. As the valve is viewed in the drawing, the spool 51 is blocking conduit 44 and also a branch conduit 54 from a conduit 55 leading from the housing 42 to a brake cylinder 56. The valve 48 is connected by a rod 57 to a lever 58 which is also responsive to the movement of link 23 and hand lever 21. Consequently, when valve 48 is shifted in either direction, pressure from pilot pump 18 and also from cylinder 41 will be available to the brake cylinder 56. This cylinder is shown in section in Fig. 2. A piston 59 within the cylinder is connected to a rod 60 and a spring 61 urges the piston to the right, as viewed in the drawing. Piston rod 60 is connected to a lever 62 which controls the movements of a cam 63. Brake shoes 64 and 65 operate within a drum 66 to control the braking of the system. The drum 66 may be either drum 10 or some other element connected to the hoist. The spring 61 in cylinder 56 tends to maintain the brakes in locked or engaged position through the cam 63. A tension spring 67 serves to release the brake shoes when pressure is introduced into the cylinder 56 through conduit 55. Consequently, it will be seen that when the control lever 21 is shifted in either direction pressure from pilot pump 18 and the reserve cylinder 41 will be instantly available to release the brake on the hoist. This tends to cut down the drag on the hoist which would otherwise result if the pilot pump itself were required to build up the pressure to shift

the brake piston 59. The outlet fluid of pilot pump 18 has the same pressure as fluid in the cylinder 41. The cylinder 41, through spring actuated piston 45, furnishes extra volume for releasing the brake quickly. Spring 46 determines the pressure.

A conduit 68 located in housing 42, is connected to the atmosphere at one end and also to conduit 55 when the valve 48 is in the position shown. However, upon shifting of valve 48 downward, the spool 49 will close the atmospheric outlet of conduit 68 and if the valve is shifted upwardly, the spool 50 will perform the same function. The valve 48 and the housing 42 are connected to conduits 15 and 16 by conduits 70 and 71, respectively. It will be seen that the line 44 from pilot valve 18 is open to line 71 through a check valve 72 and to line 70 through a check valve 73. These check valves are set at a certain pressure so that pilot pump may supply oil to make up for any leakage in the closed circuit by the pump 14 and motor 13. Bypassing relief valves 14 and 15 are provided to limit the pressure which may be exerted by the pump on the motor 13.

I claim:

1. A braking apparatus for a hydraulically operated mechanism, including a motor for driving said mechanism and a driven member, means for driving said motor, a brake for holding said mechanism against movement, means for holding said brake in engaged position, means for releasing said brake comprising a piston and cylinder, a source of pressure, a conduit connecting said source and said cylinder, a valve in said conduit for controlling the supply of liquid under pressure to said piston and cylinder, a supplementary source of pressure comprising a cylinder, a movable member within said cylinder for resisting the entrance of liquid therein, means connecting said conduit with said supplementary supply means, and means responsive to the movement of said mechanism for controlling the position of said valve and the admission of liquid under pressure to said brake releasing means.

2. In a brake system for a hydraulic mechanism including, a member to be shifted, a hydraulic motor for shifting said member operably connected thereto, a variable displacement pump for supplying liquid under pressure to operate said motor, means for controlling the direction and

rate of movement of said motor, a brake for said member to be shifted arranged to be hydraulically operated, and control means responsive to movement of said member for controlling said motor rate and directional regulating means and said brake at intervals in the movement of said member to cause stopping of said member.

3. In a brake system for a hydraulic mechanism including, a member to be shifted to cause hoisting or lowering, a hydraulic motor for shifting said member, a pressure forming means, conduit means for forming a closed circuit between said motor and said pressure forming means, an independent source of pilot pressure, and means connecting said closed system and said pilot pressure including a valve whereby a supply line to the pressure forming means in said closed system may be connected to said pilot pressure to replenish liquid in said closed system.

4. In a brake system for a hydraulic mechanism, a member to be shifted a hydraulic motor for shifting said member, a pressure forming means, conduit means for forming a closed circuit between said motor and said pressure forming means, an independent source of pilot pressure, and means connecting said closed system and said pilot pressure including a valve whereby a supply line to the pressure forming means in said closed system may be connected to said pilot pressure to replenish liquid in said closed system, and a brake means for said member arranged to be operated by said valve whereby said member is braked at predetermined points in the movement of said mechanism.

5. In a brake apparatus for a hydraulic system including a member to be shifted, a hydraulic motor device for shifting said member operably connected thereto, a pump device for supplying liquid under pressure to operate said motor device, shiftable means on one of said devices to control the displacement thereof and shiftable to control speed, deceleration and direction of the motor device, a brake for said member to be shifted arranged to be hydraulically operated, brake operating control means, and means cooperatively connecting said shiftable means and said brake operating control means to effect brake operation at the end of a deceleration movement of said shiftable means.

HARRY F. VICKERS.
